UNITED STATES PATENT OFFICE

165,114

TIE RACK

John Saxon, Toledo, Ohio

Application May 12, 1949, Serial No. 2,600

Term of patent 7 years

(Cl. D33—8)

To all whom it may concern:

Be it known that I, John Saxon, a citizen of the United States of America, residing in Toledo, in the county of Lucas, State of Ohio, have invented a new, original, and ornamental Design for a Tie Rack, of which the following is a specification, reference being had to the accompanying drawing, forming a part thereof, in which:

Fig. 1 is a front elevation of a tie rack incorporating my new design;

Fig. 2 is a plan view of the tie rack of Fig. 1; and

Fig. 3 is an end view of the tie rack of Fig. 1.

I claim:

The ornamental design for a tie rack, substantially as shown.

JOHN SAXON.
